RECTIFIER/FILTER EDUCATIONAL BOARD

Douglas C. Covert, Royal Oak, Mich., assignor to
Xerox Corporation, Stamford, Conn.

Filed May 30, 1974, Ser. No. 474,500

Term of patent 14 years

Int. Cl. D19—07

U.S. Cl. D19—62

FIG. 1 is a top right front perspective view of a rectifier/filter educational board showing my new design; and

FIG. 2 is a bottom left front perspective view thereof.

The rear of the educational board not shown is plain and unornamented.

I claim:

The ornamental design of a rectifier/filter educational board, substantially as shown.
